US00D727427S

(12) **United States Design Patent**
Alvarado et al.

(10) **Patent No.:** US D727,427 S
(45) **Date of Patent:** ** Apr. 21, 2015

(54) **VENDING MACHINE PANEL**

- (71) Applicant: **Intercontinental Great Brands LLC**,
East Hanover, NJ (US)
- (72) Inventors: **Eddin Alvarado**, Wyckoff, NJ (US);
Michael H. Haskins, Waunakee, WI (US); **Edward J. Kaczmarek, III**, Chicago, IL (US); **Mark Kwiatek**, New York, NY (US); **Manus Mulherin**, Stroudsburg, PA (US); **Thomas Michael O'Keefe**, Grayslake, IL (US); **Jonathan Ashbridge**, Leicester (GB); **Craig Jones**, Leicester (GB); **Timothy Whately**, Leicester (GB)
- (73) Assignee: **Intercontinental Great Brands LLC**,
East Hanover, NJ (US)
- (**) Term: **14 Years**
- (21) Appl. No.: **29/475,437**
- (22) Filed: **Dec. 3, 2013**

(57) **CLAIM**

We claim the ornamental design for a vending machine panel, as shown and described.

DESCRIPTION

FIG. 1 is a front perspective view of a vending machine panel, in accordance with a first embodiment of our new design;

FIG. 2 is a front elevation view of the vending machine panel of FIG. 1;

FIG. 3 is a top plan view of the vending machine panel of FIG. 1;

FIG. 4 is a bottom plan view of the vending machine panel of FIG. 1;

FIG. 5 is a left side elevation view of the vending machine panel of FIG. 1;

FIG. 6 is a right side elevation view of the vending machine panel of FIG. 1;

FIG. 7 is a front perspective view of a vending machine panel, in accordance with a second embodiment of our new design;

FIG. 8 is a front elevation view of the vending machine panel of FIG. 7;

FIG. 9 is a top plan view of the vending machine panel of FIG. 7;

FIG. 10 is a bottom plan view of the vending machine panel of FIG. 7;

FIG. 11 is a left side elevation view of the vending machine panel of FIG. 7; and,

FIG. 12 is a right side elevation view of the vending machine panel of FIG. 7.

The broken lines depict unclaimed environmental subject matter and form no part of the claimed design.
